TRANSISTOR TRAINING AID

Joe N. Champlin, Enid, Okla.

Application February 18, 1959, Serial No. 54,660

Term of patent 7 years

(Cl. D26—1)

The single figure is a perspective view of a transistor training aid showing my new design. The back, not shown, is conventional.

I claim:

The ornamental design for a transistor training aid, substantially as shown and described.
